UNITED STATES PATENT OFFICE.

GEORGE E. BISHOP, OF IUKA, MISSISSIPPI.

SHOVEL FASTENING.

Application filed October 4, 1923. Serial No. 666,562.

To all whom it may concern:

Be it known that I, GEORGE E. BISHOP, a citizen of the United States, residing at Iuka, in the county of Tishomingo and State of 5 Mississippi, have invented certain new and useful Improvements in Shovel Fastenings, of which the following is a specification.

This invention relates to certain new and useful improvements in shovel fastening, and 10 has particular reference to improved means for effectively fastening or securing shovels of plows or cultivators upon the supporting standards or feet thereof.

The primary object of the invention is to 15 provide means for effectively fastening shovels upon their supporting standards or feet, whereby the possibility of the shovel slipping or moving from proper position is effectively prevented.

20 It is well known that considerable difficulty is had in properly and rigidly securing the shovels of plows or cultivators to metallic standards or foot pieces, slippage of the shovels from their proper positions being often experienced unless considerable care and labor is taken in fitting and securing the shovels in place. It is accordingly an object of the present invention to provide means whereby shovels may be 25 attached to the supporting feet or standards of plows or cultivators, with facility and ease, and whereby the shovels are effectively held in position under all ordinary working conditions.

30 Still another object of the invention is to provide a shovel fastening which embraces the desired qualities of simplicity and durability of construction, and wherein the attachment of the shovel may be effected with 35 ease and facility without the requirement of special tools.

40 Other objects will appear as the nature of the invention is better understood, and the same consists in the novel form, combination and arrangement of parts hereinafter 45 more fully described, shown in the accompanying drawings and claimed.

In the drawings, wherein like reference characters indicate corresponding parts 50 throughout the several views,

55 Figure 1 is a fragmentary view, partly in side elevation and partly in central longitudinal section, of a metallic foot or standard having a shovel attached thereto in accordance with the present invention.

Figure 2 is a front elevational view of the device shown in Figure 1.

Figure 3 is a rear elevational view of the front or standard shown in Figure 1.

Figure 4 is a perspective view of the device shown in Figure 3, and

Figure 5 is a perspective view of the clamp member.

Referring more in detail to the drawings 5 indicates a metallic plow or cultivator 65 standard or foot, the lower end of which is forwardly curved in the usual manner and provided with a longitudinal elongated slot 6.

In accordance with the present invention 70 the standard 5 is provided with transverse corrugations or teeth 7 at opposite sides of the slot 6 for reception of transversely aligned teeth 8 formed upon the plate member 9 of a clamp of the form shown in Figure 5. 75 The plate member 9 of the clamp is provided with an opening as at 10 between the teeth 8 for reception of a bolt 11 that passes through the upper central portion of the shovel 12 and through the slot 6, a nut 13 80 being threaded upon one end of the bolt 11 for effectively clamping the plate member 9 against the rear side of the standard and for clamping the shovel 12 firmly against the forward side of said standard, with the 85 teeth 8 engaged in desired ones of the aligned notches or teeth 7.

The clamp member further embodies a post 14 that is rigid with the plate member 9 adjacent its upper edge and that is of such 90 form as to project through the slot 6 above the bolt 11, and this post 14 is provided with a cross-bar 15 upon its forward end that has a depending lip to engage over the upper end of the shovel 12 as shown in Figure 1. 95 The cross-bar 15 is of such form as to pass through the slot 6 when the clamp is turned to position said cross-bar parallel with said slot, after which the clamp is given a quarter turn so as to bring the cross-bar in position to extend transversely of the standard or foot 5 and engaging the upper edge portion of the shovel 12. The bolt 11 is then 100 passed through the shovel and standard as well as through the opening 10 of the plate member 9, after which the nut 13 is placed upon the bolt and tightened so as to engage the teeth 8 in the notches 7, whereby a lateral shifting of the shovel is effectively permitted and slipping of the shovel longitudi- 110

dinarily of the standard is rendered impossible.

From the foregoing description it is believed that the construction and operation 5 as well as the advantages of the invention will be readily understood and appreciated by those skilled in the art.

Minor changes may be made without departing from the spirit and scope of the invention as claimed. 10

What I claim as new is:—

Shovel attaching means for plow or cul-

tivator standards including a clamp composed of a plate provided with an opening, teeth extending transversely of the plate at opposite sides of said opening, a post rigid with one end of the plate and extending from one side of the latter, a cross-bar rigid upon the outer end of said post, said cross-bar having an overhanging lip to engage 15 over the upper end of a cultivator or plow shovel.

In testimony whereof I affix my signature.
GEORGE E. BISHOP.
